[57] CLAIM

The ornamental design for lens housing for portable game accessory, as shown and described.

DESCRIPTION

FIG. 1 is a perspective view of a lens housing for portable game accessory showing my new design;

FIG. 2 is a top view thereof;

FIG. 3 is a bottom view thereof;

FIG. 4 is a rear view thereof;

FIG. 5 is a front view thereof; and,

FIG. 6 is a left side view thereof, the right side view being a mirror image.

The broken lines shown in the FIGURES are environmental only and form no part of the claimed design.
